UNITED STATES PATENT OFFICE.

ROBERT W. SCOTT, OF PHILADELPHIA, PENNSYLVANIA.

KNITTED SHIRT.

SPECIFICATION forming part of Letters Patent No. 404,229, dated May 28, 1889.

Application filed June 11, 1888. Serial No. 276,664. (No model.)

To all whom it may concern:

Be it known that I, ROBERT W. SCOTT, a citizen of the United States, and a resident of Philadelphia, Pennsylvania, have invented 5 certain Improvements in Knitted Shirts, of which the following is a specification.

One object of my invention is to so make a knitted shirt that the body of the same will consist of one continuous piece, tubular in the lower portion, and having an upper portion with selvage-edged arm-holes, a further object being to make a sleeved shirt without seams save where the sleeves are secured to the body.

Figure 1 in the accompanying drawings illustrates a shirt made in accordance with my invention, the sleeves being detached from the body; and Fig. 2 is a diagram illustrating the mode of joining the front and back webs at the top of the shirt.

20 In carrying out my invention I use a machine of that class in which two parallel needle-beds placed close together are employed, and in starting to knit the shirt I carry a single thread across the machine from one end to the other, the thread being applied first to a needle of one bed and then to a needle of the other bed, so as to form connecting-threads *a*, and I then proceed to knit on each row of needles an independent web, *b*, using two thread-

25 guides, one for each row of needles, these guides traversing back and forth, so as to form a selvage at each edge of the web. When these webs have been knitted to the desired extent, additional needles are successively 30 thrown into action at the ends of each row, so as to gradually widen each web, as shown at *d*, this widening being continued until the fabrics are wide enough to form the body of the shirt. One of the thread-guides is then

35 thrown out of action, and the other thread-guide is operated, so that in moving in one direction it will deliver its thread to the needles of the front row and in its return course to the needles of the back row, the result being 40 the production of the tubular fabric, *f*, which is continued until the proper length of fabric for the body of the shirt has been completed. If a sleeveless shirt is required, it is now complete, the arm-holes being properly shaped 45 and provided with selvaged edges. If a sleeved shirt is desired, however, the sleeves *g* are

knitted tubular, and are preferably provided with ribbed cuffs *h*, and each tube when it approaches the shoulder portion is gradually widened or increased in diameter, as shown at 55 *g'*, by bringing additional needles into operation, so that when the sleeve is completed the end course of stitches is of such diameter as to conform closely in dimensions to the selvage edges *i* of the upper portion, *b b*, of 60 the body of the shirt.

Although I prefer to connect the upper edges of the independent webs forming the upper portion of the body of the shirt by applying a single thread to the needles of the two needle-beds before commencing the knitting of the webs, as above described, it will be evident that the webs may be started independently of each other on the two beds and the upper edges of the webs afterward connected 65 together by the ordinary seaming-machine, and, if desired, the upper edge of the front web may be cut out, as indicated by the dotted line *x*, to form the neck, the cut edge being afterward bound or finished in any suitable manner; or the opening may be formed with selvaged edges by starting with a narrow web at each side and gradually widening these webs on their inner edges until they 70 meet.

It will be observed that a shirt constructed in accordance with my invention is practically seamless—that is to say, it has no seams formed by sewing together cut edges of the fabric; hence it is much preferable to a garment 75 shaped by cutting and sewing in the ordinary way.

It will be evident that in carrying out my invention the knitting operations may be reversed, the shirt being started at the bottom 80 and the sleeves at the inner ends, and the webs being narrowed where they would otherwise be widened, or widened where they would otherwise be narrowed.

Having thus described my invention, what I 85 claim, and desire to secure by Letters Patent, is—

1. A knitted shirt having a seamless tubular lower portion and an upper portion, comprising front and back webs connected at the 90 top and having opposite tapered or shaped selvage edges, all substantially as specified.

2. A knitted shirt having a body with tubular seamless lower portion and an upper portion, comprising front and back webs connected at the top and having opposite selvage edges shaped as described, and sleeves consisting of seamless tubes widened at and near the shoulder portion and connected to the selvage edges of the webs forming the upper portion of the body of the shirt, all substantially as specified.

In testimony whereof I have signed my name to this specification in the presence of two subscribing witnesses.

ROBERT W. SCOTT.
